(57) **CLAIM**

The ornamental design for a wine aerator, as shown and described.

DESCRIPTION

FIG. 1 is a perspective view of a wine aerator showing our new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right-side elevational view thereof; and,

FIG. 7 is a left-side elevational view thereof.

The broken lines shown in the figure drawings are for the purpose of illustrating portions of the wine aerator that form no part of the claimed design.

1 Claim, 4 Drawing Sheets
